Fig. 6

Fig. 3

Fig. 7

Fig. 4

Fig. 8

FIG. 1 is a top plan view of a cross pendant or the like showing my new design;

FIG. 2 is a front view thereof;

FIG. 3 is a rear view; and

FIG. 4 is a side view thereof;

FIG. 5 is a top plan view of another embodiment of the cross pendant or the like shown in FIG. 1 having only one gem thereon;

FIG. 6 is a front view thereof;

FIG. 7 is a rear view; and

FIG. 8 is a side view thereof.

I claim:

The ornamental design for a cross pendant or the like, substantially as shown and described.
